UNITED STATES PATENT OFFICE

HUBERT A. SEARCY, OF LA GRANGE, KENTUCKY

WIND-OPERABLE FIGURE

Application filed October 9, 1930. Serial No. 487,605.

This invention relates to a wind-operable toy figure construction.

It is aimed to provide such an article which may serve as an ornament or novelty for use upon an automobile, for instance on the radiator cap or elsewhere and also to provide an article which may form a toy for usual use by children.

A particular object is to provide a construction wherein the figure, through the action of the wind will continuously give the effect of clog dancing.

Another object is to provide a novel construction wherein the figure in addition to having the necessary articulation and vertical movement, may also swing about a vertical axis to simulate dancing in substantially the path of a circle.

The more specific objects and advantages will become apparent from a consideration of the description following taken in connection with accompanying drawings illustrating an operative embodiment.

In said drawings:—

25 Figure 1 is a view showing the invention in side elevation.

Figure 2 is a plan view thereof,

Figure 3 is a cross sectional view taken on the line 3—3 of Figure 1,

30 Figure 4 is a cross sectional view taken on the line 4—4 of Figure 1,

Figure 5 is a side elevation of a modified form,

Figure 6 is a plan view of the form of Figure 5,

Figure 7 is a cross sectional view taken on the line 7—7 of Figure 5, and

Figure 8 is an enlarged detail sectional view illustrating the swivel connection of the articulate figure.

Referring specifically to the drawings, and first to the form of Figures 1 to 4, a bracket is employed at 10 which may have a depending stud 11 or any other means whereby it may be attached to a radiator cap on an automobile, in the event the device is used as a novelty or ornament on the automobile or it may be attached to a handle or staff if the device is to be used as a toy or otherwise. The front end 50 of the bracket 10 is vertical and doubled to

form a bearing at 12 from which a diagonal brace 13 extends and which is riveted at 14 to the remainder of the bracket, thus rendering the bearing 12 relatively rigid. At the other end of the bracket 10, a bearing 15 is riveted as at 16 to the bracket.

55 Suitably journaled in the bearings 12 and 15 against longitudinal displacement is an operating shaft 17 which has a propeller blade or wind-driven element 18 rigidly secured thereto. A vane 19 of suitable shape may be rigidly fastened as by rivets 20 to an angle 21 of the bearing 15.

Intermediate its ends, shaft 17 is provided with an offset portion or crank 22 and over the same, a platform 23 is provided, being fastened in place, for instance by a bar 24 having diagonal portions 25, the intermediate portions being rigidly secured to the bracket 10 and the terminals being riveted 60 as at 26 to the platform.

65 A supporting post 27 extends through and above the platform and below the same is laterally offset at 28 so as not to interfere with the movement of the crank 22. The lower 70 portion of the rod 27 is rigidly attached as at 29, to bracket 10.

Rod 27 has a laterally extending arm 30 provided with an eyelet 31 in the forward end thereof.

80 An articulate figure is shown at 32 which may be of any desired form and consisting of sections 33 connected together loosely by means of links or the like 34. A pitman 35 is employed and may be in sections 36 and 37, 85 the latter being rigidly connected to one of the sections 33. Section 36 of the pitman extends through an enlarged slot 39 in the platform and below the platform is pivotally connected to the crank 22 as by an eyelet 40.

80 The sections 36 and 37 are preferably connected together by a swivel as at 41, that is one which will permit the section 37 to turn on its own axis relatively to the section 36, so that the figure may dance around in substantially the path of a circle.

95 As a result of the construction described, as the automobile equipped with the invention travels, the air impinges upon the propeller 18, thus rotating shaft 17 and recipro- 100

cating the pitman 35 and accordingly moving the articulate figure into and out of engagement with the platform 23 in such manner as to simulate a clog dancer. At the same time, the figure may move in the path of substantially a circle in view of the pivotal or swivel connection at 41. The result will also be the same if the structure is held in the hand and arranged in the wind or moved so that the wind will impinge upon the blade 18.

A slightly modified construction is shown in Figures 5 to 8. In such figures, the vane 19 is dispensed with and a bearing 15^a, equivalent of the bearing 15 of the previous form, directly journals the shaft 17. All other reference characters used in connection with the previous form apply to the present one and accordingly have been placed on the drawings thereof.

Various changes may be resorted to provided they fall within the spirit and scope of the invention.

I claim as my invention:

1. An article of the class described having a bracket, a shaft journaled thereon, a driving element for said shaft adapted for impingement with the air to cause rotation thereof, a platform supported from the bracket, a rod supported from the bracket, an articulate figure coacting with the platform, a pitman connected to said figure and guided by said rod, said pitman extending through the platform, a crank on said shaft connected to the pitman, and a connection in said pitman permitting the articulate figure to follow substantially the path of a circle in operation.

2. A device of the class described comprising a bracket, a platform mounted rigidly therefrom and thereover, a shaft journaled on the bracket below the platform, a driving member for the shaft adapted for actuation by impingement with the air, a crank on said shaft, a pitman extending through the platform and connected to the crank, an articulate figure coacting with the platform and mounted by the pitman, and a swivel connection in the pitman to permit the figure to move about the axis of the pitman.

3. A device of the class described, comprising a shaft, a pitman driven by said shaft, a figure secured to said pitman, and a swivel connection in said pitman adapted to permit the figure to move around the pitman during its actuation by the shaft.

In testimony whereof I affix my signature.
HUBERT A. SEARCY.
